WINDING HEAD

Kenly C. Bugg, Farmington, Mo., assignor to
Hoosier Lamp & Stamping Corporation,
Evansville, Ind., a corporation of Indiana

Application July 5, 1934, Serial No. 733,744

12 Claims. (Cl. 140—92.2)

This application is concerned with a device and process for forming coils of wire without spools, and relates to subject-matter constituting a development of the invention set forth and 5 described in my United States Letters Patent No. 1,994,684, granted March 19, 1935. According to that prior patent, the coiled wire is formed either without any supporting member such as a spool or upon a plain core without end-flanges, the 10 turns of the coil, and especially the end turns, being held in place by loops of tape or other flexible material which embrace the end turns of the coil and are clamped within the coil between successive layers or turns of wire.

15 According to the present invention, the wire-coil is formed upon a cylindrical core clamped between two co-axial rotating heads each of which carries a series of bobbins containing the binding tape. At the beginning of the winding operation, the tapes carried by each head extend from their respective bobbins through guides arranged in an annular series and thence inwardly across the face of the head, the inner end of each tape being anchored near the adjacent end of the core. The coil is wound in the usual manner, the wire being traversed back and forth between the two heads as the heads and core are rotated. At intervals, the tape stretches extending generally radially across the 20 inner face of one head are picked up at intermediate points and drawn axially inwardly of the coil to form bights extending generally axially along the outer face of the coil. The inner end of each bight so formed is drawn beneath the stock wire which is being fed on to the coils and axially beyond such stock wire, so that it becomes clamped to the coil by successive turns of the wire. After the bight has been thus clamped, the tape is severed at the 25 inner end of the bight, and the winding of the coil proceeds.

The accompanying drawings illustrate mechanism the structural details and functioning of which embody the invention of this application: 30 Fig. 1 is a plan view of the winding device and a partly wound wire-coil with parts of the device broken away to show the construction more clearly; Fig. 2 is an end elevation of the device with one of the heads removed; Fig. 3 is a horizontal axial section through the needles which are used to form each bight of tape and draw its inner end inwardly of the wire coil; Fig. 4 is a perspective view of the device with 35 the outer head removed, showing a coil in the

process of formation; Fig. 5 is a vertical axial section through the device showing a coil partly wound; and Fig. 6 is a view generally similar to Fig. 5 but somewhat idealized to show the tape and wire on an enlarged scale.

5 In the drawings, I have not illustrated details of the coil-winding machine itself, as such machines are well known and may take a number of different forms. In general, a machine of this type comprises a rotating shaft, adapted to support the spool or other element upon which the wire is to be wound, and traversing mechanism by means of which the wire feeding on to the spool is traversed between the ends thereof.

10 In the drawings, I have indicated the rotating coil-supporting shaft of the winding machine at 10. Mounted on this shaft for rotation therewith I provide two heads 11 and 12, the outer head 12 being axially removable to permit the 15 withdrawal of a coil from between the two heads and being normally held in place as by means of a nut 13 on the threaded end of the shaft 10. Each of the heads 11 and 12 is in the form of a 20 hollow drum having a plane inner face and a 25 cylindrical annular flange 15 which extends outwardly from such inner face. Within each head there are rotatably mounted a plurality of bobbins 16 carrying the tape which is to be used in winding the wire-coils. The number of these 30 bobbins will vary to suit the circumstances, the device shown in Figs. 1 and 2 embodying six bobbins in each head while that shown in Fig. 4 embodies twelve. The flange 15 on each drum is provided with an opening 17 for each bobbin, 35 such openings serving to permit the tapes from the bobbins to be brought out of the drum. From each opening 17, the tape 18 extends axially inwardly, conveniently passing beneath a spring-metal brake 19 and thence through a guide 20, 40 the guides on each drum preferably being arranged at equal intervals to form an annular series.

45 On the inner face of each drum there is provided an inwardly extending axial boss 22 of a diameter to receive and support a hollow cylindrical core 23 upon which the wire-coil is to be formed. This core is clamped axially between the two heads 11 and 12, and the two heads and core therefore rotate as a unit when the shaft 10 50 is rotating.

55 At the beginning of each coil-winding operation, the ends of the tapes 18 carried by each drum, after being drawn beneath the respective brakes 19 and through the respective guides 20, 55

are passed radially across the face of the drum and secured near the adjacent end of the core 23. Conveniently, but not necessarily, the inner end of each tape 18 is anchored by clamping it 5 between the boss 22 and core 23, as indicated in Fig. 6.

The tape-feeding mechanism, which is disposed between the two heads 11 and 12 and surrounding the core 23 and the coil wound thereon, 10 operates to pick up each stretch of tape extending across the face of the drums to form a bight the inner end of which is drawn axially inwardly, clamped by the stock wire feeding on to the coil, and severed. This feeding mechanism is supported 15 from an arm 30 which is pivotally mounted on a horizontal axis parallel to the axis of the shaft 10. Conveniently, the arm 30 is provided with a hub 31 which receives a stationary shaft 32 supported from the frame of the machine. 20 Attached to the arm 30 is a cross-piece 33 having a length slightly less than the distance between the two heads 11 and 12, and the outer ends of the cross-piece have secured to them two upwardly extending braces 34 which support at 25 their upper ends a bridge 35 adapted to guide the stock wire 36 as it feeds on to the coil.

Attached to opposite sides of the arm 30 at the inner end thereof are two arm-extensions 38 which are of a generally semi-circular shape and 30 extend upwardly on the back side of the shaft 10 to a point above such shaft. A roller 39, mounted at the upper end of the extensions 38, rests upon the coil being formed and serves to maintain the upper ends of the extensions 38 35 and the bridge 35 in approximately constant relation to the top of the coil as the coil increases in diameter.

Also attached to the arm 30 near the inner end thereof are the superposed lower ends of 40 two needle-supports 41 and 42. These needle supports are of helical conformation and of opposite hand and extend generally upwardly on the front side of the shaft 10 to a point beneath the bridge 35.

45 The two needle supports 41 and 42 have different radii of curvature, the radius of the support 42 being shown as less than that of the support 41. This provides between the needle supports a space 43 (Fig. 2) the purpose of which 50 will hereinafter become evident.

To the upper end of the needle support 41 there is secured a helical needle 45 which is of the same hand as the support 41 and conveniently has substantially the same radius of curvature. 55 The needle 45 is spaced axially from the support 41 toward the drum 11 to provide a slot 46. From its point of attachment to the support 41, the needle 45 extends downwardly around the coil generally parallel to the support 41; and beyond 60 the point of attachment of the support 41 to the arm 30, the needle continues to extend helically and terminates in a flat or plane portion 45' disposed adjacent the face of the drum 12 and sloping forwardly and upwardly in rear of and above 65 the shaft 10.

A similar needle 48 is secured to the upper end of the support 42 and extends generally parallel to such support and spaced therefrom toward the drum 12 to provide a slot 49. Like the needle 70 45, the needle 48 continues to extend helically up the rear side of the coil and terminates in a plane portion 48' disposed adjacent the face of the drum 11 and generally parallel to the plane portion 45' of the needle 45.

75 Pivotaly mounted on a generally radial axis on

each of the plane portions 45' and 48' is a pick-up member 51. Each of these pick-up members extends from its axis of pivotal mounting in a direction opposite to that in which the shaft 10 and heads 11 and 12 rotate and terminates in a point disposed close to the inner face of the adjacent head, as is clear from Fig. 1. Springs 52, or other suitable means, act on the pick-up members 51 and serve to hold the free ends thereof normally out of contact with the faces of the respectively adjacent heads.

To prevent the pointed end of either pick-up member 51, when it is in retracted position, from accidentally engaging any of the tapes 18 extending across the adjacent drum-face, the upper ends of the extensions 38 carry guide members 55 which extend outwardly toward their respective drums and terminate closely adjacent the faces thereof. Each of these guides is provided with a notch 56 for the reception of the extreme end of the pick-up member 51. In the retracted position of each pick-up member, the extreme end thereof lies in the notch 56 at a greater distance from the face of the adjacent drum than is the tape-guiding face of the guide 55, the guide thus serving to carry the tape 18 past the end of the pick-up member.

For actuating the pick-up members 51 to force them outwardly into contact with the inner faces of the heads 11 and 12, various means may be employed. In the drawings, such means is shown as taking the form of small flexible tubes 60 which are adapted for connection, through suitable control means, to a source of air under pressure. The tubes 60 may be secured to the extensions 38, their upper ends being disposed respectively adjacent the inner faces of the heads of the pick-up members 51, so that air expelled from either tube 60 will force the associated pick-up member into contact with the face of its adjacent head.

When a coil is to be wound, a core 23 is inserted and clamped between the two heads 11 and 12, the free ends of the tapes 18 being brought radially across the faces of the heads and secured adjacent the core, as above set forth. The winding of the coil is then started at one end of the core 23, Fig. 6 indicating the winding as starting at the left-hand end of the core or adjacent the head 11. After the winding has progressed for a requisite number of turns, the tube 60 associated with the pick-up member 51 on the needle 48 is connected to the source of air under pressure with the result that that pick-up member 51 on the end of the needle 48 is swung about its axis of pivotal mounting to bring its pointed end into contact with the face of the drum 11. As the drum 11 continues to rotate, the tapes 18 are successively picked up and passed over the end of the needle 48 as indicated in Fig. 1. Each bight of tape thus formed is drawn axially inwardly of the coil by the needle 48, tape for forming the lengthening bights being supplied from the bobbins 16. As each bight passes below and beyond the shaft 10, its outer stretch is engaged by the support 34 and forced inwardly to pass beneath the bridge 35. As it emerges from beneath the bridge 35, each bight is engaged by the stock wire 36, which is feeding on to the top of the coil, and thus clamped in place.

As the heads rotate during the formation of a bight, the inner end of the bight is carried circumferentially through the slot 49 between the needle 48 and its associated support 42. The parts are so arranged that the bight, or at least

the outer stretch thereof, is engaged by the feeding stock wire 36 before the inner end of the bight reaches the end of the slot 49, at which point there is located a knife 65 which serves to sever 5 the tape.

The pick-up member 51 is held in contact with the face of the drum 11 for one revolution thereof, so that all the tapes on the drum 11 are drawn inwardly in bight-form and severed. When, at 10 the conclusion of this revolution of the head 11, air flow through the tube 60 is shut off, the spring 52 retracts the pick-up member and winding of the coil proceeds with the tapes again extending generally radially across the face of the head 11. 15 The operation of the pick-up members 51 may be manually controlled through the medium of a manually operated valve regulating the supply of air to the tubes 60; or such members may be automatically actuated, as by the provision of a 20 valve controlled by the traversing mechanism. In either event, the pick-up members should not be held in contact with the drum-faces respectively associated with them for more than a full revolution of the drums, as otherwise a duplication 25 of tape-bights would be produced.

As pointed out in my prior application above referred to, the tape or other binding material may take various forms. In general, any relatively thin flexible material sufficiently strong will be 30 satisfactory; but I have found to be most suitable the so-called "printed string" which is commonly used in the tying of packages.

The tape-engaging surfaces of the needles 45 and 48 and of the supports 34 should preferably be smooth and highly polished in order to decrease the frictional drag on the tapes passing over them. This frictional drag causes the inner 35 end of each tape-bight to lag behind the outer end, thus giving each bight a helical inclination. By decreasing friction between the tape-bights and the surfaces which engage them, this helical 40 inclination may be prevented from becoming excessive; but I do not regard a reasonable degree of helical inclination as objectionable and it may even have an advantage in the action of the tapes 45 in preventing snarling of the wire when it is withdrawn from the coil by an axial take-off as contemplated in both this and my prior application.

It is to be noted that the two needles 45 and 48 50 cross each other and that the tape-bights at each end of the coil therefore overlap. It is to permit the tapes on the needle 45 to pass the needle 48 and those on the needle 48 to pass the needle 45 that the needles are made of different radii of curvature to provide the space 43; as the outer 55 stretch of each bight extends through such space as the bight reaches the end of the needle which forms it. Obviously, the overlapping of the tape-bights ties the two ends of the coil together and 60 prevents any axial separation.

In a coil produced as above described the end turns are held in place by loops of tape which embrace them. The number of layers of wire embraced by each tape-loop will vary to suit circumstances. In general, the heavier the wire the 65 fewer layers will be embraced by each tape-loop.

Similarly, the number of tapes used is susceptible of considerable variation. To prevent too great an axial extent of an end turn of wire from 70 being unsupported, larger-diameter coils of wire will require tape at more frequent angular intervals than will smaller-diameter coils.

To secure the binding by tape-loops of the extreme end turns of the inner layer of wire without 75 the necessity for securing the extreme inner

ends of the tapes to the core by some special means, the winding may be started near the center of the core and progressed with toward one end of the core. Before the winding reaches that end of the core, however, a series of tape-bights 5 is drawn inwardly from that head toward which the winding is progressing and bound down against the core by later-deposited turns of wire. The inner stretches of such bights, embracing no wire-turns, are of no value in holding the coil 10 together; but the outer stretches, which are securely bound, form the inner legs of loops which will embrace the end turn of the inner wire-layer as well as the end turns of as many additional layers as may be desired. As the winding 15 nears the opposite end of the core, but before it reaches such opposite end, the tapes on the other head are drawn inwardly and bound against the core in the same manner.

In the arrangement illustrated in the drawings, 20 it is contemplated that the core 23 will remain within the coil; but this, as pointed out in my prior patent, is not necessary. It is preferred, however, in the case of wire of relatively small 25 diameter.

Upon the completion of the winding of the coil, it is removed from between the two heads. Any loose ends of tape which do not embrace 30 turns of the coil may be removed or cut off, and the last turns of wire may be secured to the coil 35 in any convenient way, as disclosed in my prior patent.

I claim as my invention:

1. In a coil-winding device, a pair of co-axial 35 rotatable heads having opposed faces between which is supported the coil being wound, means on each head carrying a plurality of tapes each of which extends generally radially across the face of its associated head, and means located 40 between said heads, and operable to engage successively the tapes extending across the face of one of said heads, form bights in such tapes, draw such bights axially inwardly over the outer surface of a coil between said heads, and then sever the tapes at the inner ends of the bights. 45

2. In a coil-winding device, a pair of co-axial rotatable heads having opposed faces between which is supported the coil being wound, means on each head carrying a plurality of tapes each of which extends generally radially across the face 50 of its associated head, means located between said heads and operable to engage successively the tapes extending across the face of one of said heads, form bights in such tapes, and to draw such bights axially inwardly over the outer surface of a coil between said heads, mechanism for feeding wire on to such coil to bind the bights thereto, and means for severing the tape at the inner end of each bight after such bight has been 55 so bound to the coil. 60

3. In a coil-winding device, a rotatable head having a face against which is disposed one end of a coil being wound, means on said head carrying a plurality of tapes each of which extends 65 generally radially across the face of said head, and means operable to engage successively the tapes extending across the face of said head, form bights in such tapes, draw such bights axially inwardly over the outer surface of a coil between said heads, and then sever the tapes at the inner 70 ends of the bights.

4. In a coil-winding device, a rotatable head having a face against which is disposed one end of a coil being wound, means on said head carrying a plurality of tapes each of which extends gen- 75

- erally radially across the face of said head, means operable to engage successively the tapes extending across the face of said head, form bights in such tapes, and to draw such bights axially inwardly over the outer surface of a coil between said heads, mechanism for feeding wire on to such coil to bind the bights thereto, and means for severing the tape at the inner end of each bight after such bight has been so bound to the coil.
5. In a coil-winding device, a rotatable head having a face against which is disposed one end of a coil being wound, means on said head carrying a plurality of tapes each of which extends generally radially across the face of said head, a helical member extending axially inwardly of the coil from a point adjacent the face of said head, and means operable to pick up the tapes extending across the face of the head and to guide them over the adjacent end of said member.
10. 5. In a coil-winding device, a rotatable head having a face against which is disposed one end of a coil being wound, means on said head carrying a plurality of tapes each of which extends generally radially across the face of said head, a helical member extending axially inwardly of the coil from a point adjacent the face of said head, and means operable to pick up the tapes extending across the face of the head and to guide them over the adjacent end of said member.
15. 6. The invention set forth in claim 5 with the addition of means located near that end of said member which is remote from said head for severing the tape, said means comprising a knife on the cutting edge of which the end of the tape-bight is guided by said member.
20. 7. The invention set forth in claim 5 with the addition of means located near that end of said member which is remote from said head for severing the tape.
25. 8. The method of forming a coil of wire having a plurality of layers each embodying a multiplicity of turns, which comprises winding the wire over the ends of a plurality of tapes which ex-

tend outwardly beyond the coil, forming a bight in the outwardly extending portion of each tape, drawing each of said bights axially inwardly of the coil, and then binding said bights in place by winding wire over them.

9. The method set forth in claim 8 with the addition of severing each tape near the inner end of the bight after such bight has been bound in place.

10. In a coil-winding device, a pair of co-axial 10 rotatable heads having opposed faces between which is supported the coil being wound, means on each head carrying a plurality of tapes each of which extends generally radially across the face of its associated head, and means located 15 between said heads and operable to engage successively the tapes extending across the face of one of said heads, form bights in such tapes, and draw such bights axially inwardly over the outer surface of a coil between said heads.

11. In a coil-winding device, a frame, a coil-support rotatably mounted in said frame, means rotatable with said coil support for carrying a flexible tape, and means supported from said frame and operative in the rotation of said coil-support for forming a bight in said tape and drawing such bight axially inwardly and depositing it upon the outer surface of a coil on said support.

12. The invention set forth in claim 11 with the addition of means for severing said tape at the inner end of a deposited bight.

KENLY C. BUGG.
